By

UNITED STATES PATENT OFFICE.

GUSTAF HOLMBERG, OF OMAHA, NEBRASKA.

DESIGN FOR A MACHINE-STAND.

42,625.

Specification for Design.

Patented June 18, 1912.

Application filed January 2, 1912. Serial No. 669,101. Term of patent 14 years.

To all whom it may concern:

Be it known that I, GUSTAF HOLMBERG, a citizen of the United States, residing at Omaha, in the county of Douglas and State of Nebraska, have invented a new, original, and ornamental Design for a Machine-Stand, of which the following is a specification, reference being had to the accompanying drawing, forming a part thereof.

Figure 1 is a front view of a machine stand, showing my new design Fig. 2 is an

end view of the machine stand, and Fig. 3 is a perspective view of the same.

I claim:

The ornamental design for a machine stand, as shown.

In testimony whereof I have affixed my signature in presence of two witnesses.

GUSTAF HOLMBERG.

Witnesses:

HIRAM A. STURGES,
A. F. CLARK.
